UNITED STATES PATENT OFFICE.

GILBERT C. BEMIS, OF WORCESTER, MASSACHUSETTS, ASSIGNOR OF ONE-HALF TO
EDWARD F. FLETCHER, OF WORCESTER, MASSACHUSETTS.

BRUSH.

1,100,113.

Specification of Letters Patent. Patented June 16, 1914.

Application filed October 1, 1912. Serial No. 723,342.

To all whom it may concern:

Be it known that I, GILBERT C. BEMIS, a citizen of the United States, and a resident of Worcester, in the county of Worcester 5 and Commonwealth of Massachusetts, have invented certain new and useful Improvements in Brushes, of which the following is a specification.

The object of this invention is the construction of certain improvements in brushes whereby the bristles are readily replaced, adjusted and secured in place; the same being specifically adapted for cylindrical brushes used for cleaning large guns and the like.

15 Referring to the drawings forming part of this specification, Figure 1 is a cross section of a cylindrical brush provided with the brush-units embodying the essential features of my improvements. Fig. 2 is a plan view of one form of the brush-unit cylinders. Fig. 3 is a longitudinal section of the same. Fig. 4 is a similar section showing the cylinder after it has received the crimping which serves to fasten the bristles in the 25 same.

A brush-unit consists of a cylinder or shell 1 adapted to have the bristles or wires 2 fastened therein by the peripheral compression of the shell at a line intermediate of 30 its ends, at 3 in Fig. 1. When the bristles are of woody fiber or animal origin, such compression is sufficient to secure the same strongly in place, but when they are of wire or thin ribbon metal, I find it advisable to 35 insert a plug 4 in the heart of the bunch of bristles, in which plug is an annular groove coinciding in general position with the intended peripheral compression of the shell. Then when the shell is compressed after the 40 wires and plug have been inserted therein, the wires will be forced more or less into the groove in the plug and by such lateral distortion will be locked against withdrawal. By having the outer end of the plug rounded as shown in Fig. 1, the bristles or wires 45 will bend over such end when forced inward by operative pressure, but will spring back when the pressure is removed and will not receive a permanent set or bend, as would be 50 the case were the end of the plug a right-angled edge. The groove 5 in the plug is, it

will be further noted, not a deep one into which the wires might be bent so sharply as to cause their fracture and consequent falling out, but the groove is shallow and 55 rounded so that the wires cannot be forced therein beyond their safe limit. I have found that it is necessary to form the shell 1 with an outwardly extended flange 6, as shown in Figs. 1 to 4, or else to provide it 60 with a bottom 7 in order to sustain the shell against distortion when receiving the peripheral depression 5, since otherwise the shell will be crushed out of its cylindrical shape. In order to employ these brush-units 65 for cleaning out large pieces of ordnance, I provide a cylindrical head 10 having numerous radial holes 11 fitting the shells 1. In case the shells are formed with the flanges 6, the brush-units are secured adjustably in 70 said holes by means of spring cushions 12 seated on the bottoms of said holes, and screws 13 passing through said flanges and tapped into the head 10, as illustrated in Fig. 1. When said screws are unloosened, 75 said springs force the brush-units outward more or less, while an inward turning of said screws reduces the operative diameters of the brushes. I have found that by using a longer or shorter plug 4, the spread of the 80 bristles 2 can be varied considerably, the longer plugs spreading the outer ends of the bristles more than the shorter plugs whose outer extremities stop nearly flush with the shells 1. 85

What I claim as my invention and for which I desire to secure Letters Patent is as follows, to wit:—

A brush comprising a cylindrical shell having an integral radially projecting extension at one end, bristles in said shell, and a plug located centrally within the bristles, the shell being peripherally compressed at an intermediate point of its length. 90

In testimony that I claim the foregoing 95 invention, I have hereunto set my hand this 29th day of August, 1912.

GILBERT C. BEMIS.
